PAPER FEEDING MECHANISM

Francisco Campos, Paris, France

Application November 1, 1934, Serial No. 751,102
In Great Britain November 1, 1933

5 Claims. (Cl. 197—128)

This invention relates to mechanism for feeding a continuous sheet or web of paper from a storage roll in typewriters, tabulating and other printing machines, and has for its object to provide means imparting a long feeding operation to the paper at predetermined intervals. Such continuous sheets or webs are frequently divided into sections of equal length, each section constitutes a form having a heading or other matter occupying the same space on each form.

In printing items on such forms the first item on a form should be immediately below the heading and after a series of items has been printed on the form it is necessary to impart a long feed movement to the web of paper to bring the next form into position to receive its first item immediately beneath the heading. Consequently the extent of the long feeding movement will vary with the number of items printed on each form and is equal to the total form length, less the length occupied by the items printed on the form.

According to the present invention the extent of the long feed is controlled by the paper itself which, to this end, is provided with cut away portions and is given a long feeding movement by feed rolls narrower than the cut away portions and acting on the paper in the path of the cut away portions, whereby when the cut away portions reach the feed rolls, the latter no longer grip the paper, which consequently ceases to move despite the fact that the rolls may continue to rotate. In the present instance these cut away portions are shown as round holes punched out at the line of intersection of the bill heads or the like which make up the web.

Apparatus according to the invention may comprise line spacing mechanism for feeding the sheet line by line during the item printing operation and relatively narrow auxiliary feed rolls inoperative during the line spacing operation, but adapted to grip the paper to pull the latter through the line spacing mechanism until movement of the paper is arrested owing to the cut away portions reaching the auxiliary feed rolls.

The auxiliary feed rolls may be hand or power operated and in the case of a machine printing items together with a total thereof, the auxiliary feed rolls may be caused to grip the paper and rotate to effect a long feeding operation automatically on the occurrence of a total taking operation.

Alternatively when a form length has been filled with items, the auxiliary feed rolls may be brought into operation automatically to feed the

sheet forward to the extent of the heading on the next sheet. To this end a cyclic control device as described in British Patent specification No. 328,319, may be employed to actuate the auxiliary feed rolls after a predetermined number of operations of the machine, i. e. a number equal to the number of items which one form length is capable of receiving.

The invention also includes as a further feature means for feeding a tally roll or journal sheet past the platen simultaneously with the form sheet and for maintaining the journal sheet stationary during the long feeding movement of the form sheet.

To this end, the journal sheet and form sheet are led from their respective storage rolls through the platen and line spacing mechanism together, two ink ribbons being provided to effect printing on both sheets. The journal sheet is then led to a take-up roll while the form sheet is led to a long feed mechanism as described above.

As the first item of one series must appear on the journal sheet immediately below the last item of the preceding series, it is not required to impart any movement to the journal sheet during the long feeding of the form sheet. Consequently according to the invention means is provided for separating the feed rolls of the line spacing mechanism during the long feeding operation so that the form sheet can be pulled through the line spacing mechanism without dragging the journal sheet with it.

Conveniently the mechanism for causing the auxiliary feed rolls to grip the form sheet may also be connected to the line spacing feed rolls so as to cause these to separate when the auxiliary rolls grip the paper.

One form of the invention will now be described by way of example as applied to a book-keeping machine of the kind described in British Patent specification No. 377,957.

This form of the invention, however, is embodied in paper feeding mechanism, which also incorporates means for feeding ledger sheets as claimed in British Patent No. 428,062.

Accordingly, in the present specification both the mechanism according to the present invention and the mechanism claimed in the cited British Patent 428,062 will be described and illustrated, although the mechanism according to the present invention can, if desired, be constructed as an entirely separate device without the ledger sheet feeding mechanism.

In order that the invention may be more clearly understood reference will now be made

to the accompanying drawings which show by way of example preferred embodiments thereof.

In the drawings:—

5 Figs. 1 and 1a together illustrate the mechanism in side elevation;

Figs. 2 and 2a together illustrate the mechanism in plan;

Fig. 3 shows the mechanism in front elevation;

10 Fig. 4 is a detail view of the feed rolls in their normal position;

Fig. 5 shows the feed rolls in the positions which they occupy during a long feeding operation;

15 Fig. 6 shows the feed rolls in the positions which they occupy when feeding a ledger sheet into the platen;

Fig. 7 is a view showing the form sheet passing between the long feed rolls;

20 Fig. 8 is a detail view showing the mounting of one of the small rolls by means of which the long feed is effected;

Fig. 9 is a diagram showing the path of the ribbon through the mechanism; and

25 Fig. 10 is a cross section on the line X—X of Fig. 2 showing the device for punching holes in the ledger sheets and the sensing pin and associated mechanism cooperating with these holes to stop the ledger sheet in the desired position.

30 Fig. 11 is a plan view of a stack of fan fold sheets showing the holes for controlling the positioning of the sheets.

Fig. 12 is a view of the report printed on a fan fold form showing also the relation between the fan fold feed rolls and the feed control holes.

35 In the drawings like reference numerals designate the same or similar parts.

40 In the construction shown in the drawings the journal sheet 1 and the form sheets 2 are led from their respective rolls (not shown) under the platen 740 (Figs. 1, 2, 4 and 5) which is attached to the lever 889 secured to a shaft 890. By rocking the shaft 890 as described in specification No. 377,957, the platen can be raised clear of the paper when a line spacing operation is to be effected, although this arrangement forms no part of the 45 present invention and will not be further described.

50 In passing under the platen each of the two sheets 1 and 2 passes over a length of ribbon 5a, 5b, (Fig. 9) respectively which may be arranged and fed in any known manner.

55 Since, however, the mechanism illustrated in the drawings also embodies apparatus for feeding a duplicate ledger sheet which forms the subject matter of the claims of the cited British Patent No. 428,062, the ribbon lengths 5a and 5b are made continuous with a third ribbon length 5c. The ribbon 5c however serves only to effect printing on the duplicate ledger sheets as will be hereinafter described, and would be omitted if the apparatus were restricted solely to the subject matter of the present invention, namely the means for feeding the sheets 1 and 2.

60 The two sheets 1 and 2 are led from the platen between a pair of main feed rolls comprising a driving roll 6 (Figs. 3, 6 and 7) and a driven roll 7. The driving roll 6 is mounted on a shaft 8 and may be moved step by step by any known line spacing mechanism, such for example as that described for moving the roll 741 in British Patent specification No. 377,957.

65 The driven roll 7 is freely mounted between a pair of arms 9 pivoted on a shaft 10 fixed to the frame of the machine, a spring 11 being provided 70 which tends to maintain the rolls 6 and 7 in

engagement. After passing between the rolls 6 and 7 the journal sheet 1 is then led round the driving feed roll 6 in close contact therewith and after passing under a guide roll 12 is led to a storage roll (not shown).

75 The form sheet 2 after passing between the feed rolls 6 and 7 is led between two guide plates 14 and 15 supported by two arms 32 which carry the feed roll shaft 8. Mounted in apertures 16 in the inner guide plate 14 in the manner shown in Fig. 8 are two small rolls 17 and in the outer guide plate 15 there are formed apertures 18 opposite the small rolls 17.

10 The form sheet 2 passes outside the small rolls 17 and thence between the guide plates 14 and 15 15 and over a guide roll 19 to a storage roll (not shown).

15 The outer guide plate 15 for the form sheet is curled over at its upper end to form a hinge bead 15a through which passes a rod 15b carried in a 20 bracket 15c there being provided a spring 15d whereby the plate 15 is maintained in position against the sheet 2.

25 Owing to the hinge construction the plate 15 can be swung about the hinge rod 15b to enable 25 the end of a new roll of paper, constituting the form sheet, to be inserted.

30 In operation the two sheets are fed under the printing platen so that the form sheet is in such a position that the first item printed thereon will 30 be immediately below the heading on the first form on the sheet.

35 A series of items is then printed, these being recorded simultaneously on both the journal sheet and on the first form by means of the ink ribbons 5a, 5b. After the printing of each item the main feed roll 6 advances the two sheets simultaneously one line space.

40 After the series of items has thus been printed it is desired to leave the journal sheet 1 in position so that the first item of the next series will be printed immediately below the last item of the preceding series, but it is desired to impart a long feed to the form sheet 2 to an extent equivalent to the unused portion of the first form, together with 45 the heading on the second form, in order that the first item of the second series may be printed immediately below the heading on the second form.

50 In order to effect this long feeding operation a pair of auxiliary feed rolls 21 is disposed adjacent to but normally separated from the small rolls 17 for the form sheet 2 and means is provided for separating the main feed rolls 6 and 7 and moving the auxiliary feed rolls 21 to cause the form sheet 2 to be gripped between the auxiliary feed rolls 21 and the small rolls 17 over which the sheet 2 passes. Rotation of the auxiliary feed rolls 21 then feeds the form sheet to the extent of the 55 desired feed, the length of this feed being determined as described below, while the journal sheet 1 remains stationary.

55 The auxiliary feed rolls 21 are secured to a shaft 22 freely mounted in a pair of arms 23 pivoted on a shaft 24. The rolls 21 are driven from a pulley 25 secured to a shaft 25a through 60 the following gearing.

65 Secured to the shaft 25a is a gear wheel 26 meshing with a gear wheel 27 secured to the 70 shaft 24. On the other end of the shaft 24 is a gear wheel 28 meshing with a gear wheel 28a secured to the shaft 22 carrying the auxiliary rolls 21 (see Figure 3).

75 The pulley 25 is rotated by means of a belt 29 75

from a pulley 30 driven from a source of power in the machine, such as a motor, through a clutch device which will be described later.

In order to determine the length of the long feed imparted by the auxiliary feed rolls to the form sheet, the latter is provided with holes 31 disposed in those parts of the sheet over which the auxiliary rolls 21 operate, and these auxiliary rolls are made of a width smaller than the width of the holes. Consequently whether the auxiliary feed rolls 21 continue to rotate or not, the long feed movement of the form sheet will cease as soon as the holes 31 in the sheet meet the rolls 21. When this occurs the paper ceases to be gripped between the small rolls 17 and the auxiliary rolls 21 which meet through the holes 31 without touching the paper, of which the movement consequently ceases. The holes 31 in the paper are, therefore, disposed at intervals in the sheet equivalent to the length of one form, their actual positions being at the bottom of the heading of each form.

After the long feeding operation has been completed, the auxiliary feed rolls 21 are separated from the small rolls 17 and the main feed rolls 6 and 7 are brought together again.

Before printing the first item of the next series a feed equal to one line space is effected by the main feed roll 6 to bring the journal sheet into position to receive the first item immediately below the last printed item. As this feed is also imparted to the form sheet the holes controlling the extent of the long feed may be placed on a line with the bottom of the form heading so that the form sheet stops after the long feed with the bottom of the heading in printing position. The subsequent single line feed will then bring the form sheet in position to receive the next item just below the heading as is desired.

Preferably a single control mechanism is provided for separating the main feed rolls 6 and 7 and simultaneously moving the auxiliary feed rolls 21 to grip the form sheet 2 or vice versa. This control mechanism will now be described.

The main feed roll 6 and its line feeding mechanism is carried between a pair of arms 32 freely mounted on the shaft 890. Secured to the shaft 890 is a bell crank of which one arm 34 lies under a pin 35 on one of the arms 32. The other arm 36 of the bell crank is connected by a rod 37 to a lever 38 pivoted to the machine frame at 39.

Pivoted to the machine frame at 40 is a control handle 41 having a relatively long lateral arm 42 and a short lateral arm 43.

This handle 41 is adapted to control both the mechanism for long feeding the form sheet 2 and simultaneously maintaining the journal sheet 1 stationary, and also the mechanism for feeding the duplicate ledger sheets which forms the subject matter of the claims of cited British Patent No. 428,062.

Certain parts of the control mechanism embodying the handle 41 (e. g. the long arm 42) therefore pertain only to the ledger feed mechanism while other parts are associated only with the mechanism for feeding the sheet 2 and simultaneously maintaining the sheet 1 stationary.

Thus by turning the handle 41 counter-clockwise in Fig. 2 the duplicate ledger sheet is fed in and the sheets 1 and 2 are unaffected, whereas by turning the handle clockwise the duplicate ledger sheet is fed out reversely, while the form sheet 2 is given a long feed

movement, the journal sheet 1 being unaffected.

At the present stage, those parts of the control mechanism which are used for the control of the sheets 1 and 2 only will be described, and later, in order to render the description of the mechanism complete as a whole, those parts thereof which are used for controlling the ledger feed will be described.

When the handle 41 is turned clockwise in Figure 2 the short arm 43 engages with a pin 44 on the underside of the lever 38 and turns this lever in a counter-clockwise direction, whereby the rod 37 is pulled to the right whereby the bell crank 34, 36 is turned counter-clockwise and the arms 32 are raised to lift the feed roll 6 clear of the sheets 1 and 2.

The normal position of the feed roll 6 and its associated mechanism is shown in Figure 4 and the position of these parts after the feed roll 6 has been raised by movement of the handle 41 as described above is shown in Figure 5.

The extent of upward movement of the roll 6 is such that when the roll 6 is in the raised position shown in Fig. 5 the bead 15a on the 25 guide plate 15 comes into register with notches 23a formed in the arms 23 supporting the auxiliary feed rolls 21.

Attached to a block 45 secured to the frame is a bracket 46 and connected between the top of this bracket and a pin 48 on a rod 49 connecting the arms 23 is a spring 50. When the bead 15a comes into register with the notches 23a the arms 23 are rocked counterclockwise about the shaft 24 whereby the auxiliary rolls 21 are brought into contact with the form sheet 2 which is thus gripped between the auxiliary rolls 21 and the small rolls 17.

The auxiliary feed rolls 21 are then rotated and the long feeding movement of the form 40 sheet occurs, this ceasing when the holes 31 in the sheet 2 reach the auxiliary rolls 21, whereupon the rolls 17 and 21 meet through the holes 31 and no longer grip the paper.

The auxiliary feed rolls 21 are preferably 45 set in motion by the same movement of the handle 41 as that which raises the feed roll 6.

To this end there is mounted on the pivot 40 below the handle 41 a triangular member 51 having a tail 52. The tail 52 extends between two 50 screws 53, 53a, projecting from the handle 41.

When the handle is turned clockwise to set the mechanism for a long feeding operation, the lever 38 is first operated as described above and then towards the end of the movement the screw 53 55 engages with the tail 52 and further movement of the handle rocks the triangular member 51 in a counterclockwise direction, the extent of movement being limited by a stop 54 secured to the machine frame.

The triangular member 51 is connected by a link 55 to a lever 55a for operating a clutch to connect the pulley 30 from which the rolls 21 are driven to a pulley 56 driven from a constantly rotating shaft 790 which may be driven by any 65 suitable prime mover, through a belt 57.

The pulleys 30 and 56 (Figs. 4, 5, 6 and 10) are provided with clutch dogs 30a and 56a respectively and the clockwise movement of the handle 41 which raises the feed roll 6 into the position shown in Figure 5 also moves the pulley 30 so that its dogs 30a engage with the dogs 56a on the driving pulley 56 whereby the auxiliary feed rolls 21 are rotated.

From the foregoing description it will be seen 75

- that for each series of items the form sheet is fed to the same extent whatever the number of items on the sheet, and this feeding operation is divided into two portions, one comprising the line by line feeding operation occurring during the printing of items, and the other the long feed to an extent equivalent to the distance between the last item of the series and the next pair of holes in the sheet.
- 10 During the long feeding movement of the form sheet 2 the journal sheet 1 is unaffected since the small rolls 17 do not touch the journal sheet and during the long feeding movement the feed roll 6 is not driven but is free to rotate idly.
- 15 After the long feeding movement has ceased the handle 41 is returned to its normal position whereupon the feed roll 6 descends to its normal position under the action of gravity. This movement also returns the lever 38, and the pin 44 on this lever returns the triangular plate 51 to its normal position thereby disengaging the clutch members 38a, 56a.
- The foregoing has described the long feed mechanism according to the present invention.
- 25 In order to render the operation of the mechanism clear as a whole the ledger sheet feed mechanism claimed in British Patent No. 428,062 will now be described.
- These ledger sheets 58 are folded double prior to insertion in the mechanism and in order to feed the double sheets 58 to the platen a driving feed roll 59 is provided on the shaft 24 and is normally spaced away from a driven feed roll 60 mounted on a shaft 61 carried between the pair of arms 8 which are acted upon by the springs 11. Normally the feed roll 7 carried by these arms bears against the paper passing round the feed roll 6 whereby the feed rolls 59 and 60 are held apart.
- 30 With the feed rolls in this position the sheet 58, which is first folded double so that its upper edge 58a projects beyond the lower edge, is fed by hand between the separated rolls 59 and 60 so that the upper edge 58a passes over a comb plate 62 while the lower edge passes beneath said plate.
- 35 The comb plate 62 extends across the path of the paper and is carried at the ends of arms 63 freely pivoted at 64 to the arms 32 (see Fig. 10).
- Extending upwardly from one of the arms 63, 50 which carry the comb plate 62, is a rod 65 connected by a spring 66 to a pin 67 projecting from the associated arm 32.
- When the arms 32 are in their lowermost position shown in Figures 4 and 10 the comb plate 62 55 is down in its lowermost position.
- On the underside of each arm 63 is a lug 63a and between each lug 63a and the respective arm 63 is threaded the ribbon 5c. The ribbon is also supported on small fingers 63b projecting from the rear edge of the comb plate 62.
- In the construction now being described this 60 ribbon 5c is a continuation of the ribbons 5a, 5b, used to print an impression on the journal sheet 1 and the form sheet 2 already described.
- 65 The mechanism for feeding the ledger sheets, however, may be used entirely by itself, in which case it will be understood that the ribbon may be fed back and forth from two spools in the manner of an ordinary typewriter ribbon.
- 70 Whether the ribbon 5c is used by itself, or constitutes a continuation of the ribbons 5a, 5b this ribbon 5c passes from one spool 100 over a guide roller 70 carried at the lower end of a plate 71 depending from one of the arms 32 (Figs. 1 and 9) 75 supporting the feed roll 6 and thence over a guide

roller 72 mounted at the side of the machine frame adjacent the type elements.

From the guide roller 72 the ribbon passes under the lugs 63a on the arms 63 and over the fingers 63b projecting from the rear of the comb plate 62 and thence over a guide roller 73 mounted at the opposite side of the machine frame and thence over another roller 74 supported at the lower end of a plate 75 depending from the other arm 32 supporting the roll 6.

As can be seen from Fig. 9 the rolls 70, 74, are located below the rolls 72, 73, when the feed roll 6 is in its lowermost position. By means of this arrangement the ribbon 5c is maintained close to the type elements when the feed roll 6 is in the lowermost position shown in Fig. 4, i. e. the printing position.

If, as shown in the drawings, the ledger feed mechanism claimed in the cited Patent 428,062 is incorporated with the mechanism claimed in the present application the ribbon 5c after passing over the roll 74 is passed over a roll 74a on the plate 75 and is then led across the machine to form the ribbon length 5b, then over a roll 74b on the plate 71 and back across the machine to 2 form the ribbon length 5a, after which it passes over a roll 74c on the plate 75 and thence to the other spool 100a. If, however, the ledger feed device claimed in the above cited patent is employed alone the ribbon after passing over roll 74 3 would go directly to the spool 100a.

After the double sheet 58 has been fed in by hand until its upper edge lies over the comb plate 62, it is fed under the platen 140 to the printing position automatically by means of the 3 feed rolls 59 and 60. In order to permit this feeding operation it is necessary to raise the ribbon 5c from the type elements, since the upper half of the double sheet passes over the ribbon while the lower half passes under it.

To this end the arms 32 supporting the feed roll 6 are raised to their uppermost position as shown in Fig. 6. With the feed roll 6 in this position the springs 11 turn the arms 8 clockwise until the double sheet is gripped between the rolls 59 and 60. Simultaneously the lifting of the arms 32 brings the ribbon guide rolls 70, 74 up into a position level with the rolls 72 and 73 so that the ribbon lying across the lugs 63a on the arms 63 supporting the comb plate 62 is slackened.

Further, by means of a pin 76 on the arm 32 which engages with the rod 65 the comb plate 62 is raised slightly, whereby the now slackened ribbon is raised clear of the type elements by the fingers 63b to permit the lower half of the double sheet to pass between the type elements and the ribbon.

At the same time the raising of the arms 32 which carry rolls 74a, 74b, 74c over which the ribbons 5a, 5b pass has lifted the other two ribbons 5a, 5b clear of the ribbon 5c so that the upper half of the sheet 58 can readily pass above the ribbon 5c.

The lifting of the feed roll 6 to the highest position (Fig. 6) is effected by moving the handle 41 counterclockwise in Fig. 2. When the handle is thus moved counterclockwise the longer arm 42 on the handle engages the pin 37a on the lever 38 and turns the lever 38 in a counterclockwise direction, whereby the arms 32 carrying the feed roll 6 are raised through the agency of the rod 37 and bell crank 34, 36 as already described.

The arms 32 and, therefore, the rolls 6 are however lifted higher when the handle 41 is 75

turned counterclockwise than when it is turned clockwise, the stop 54a which limits counterclockwise movement of the handle being spaced further from the handle than the stop 54. Counterclockwise movement of the handle raises the roll 6 to the position of Fig. 6 whereas clockwise movement of the handle raises the roll to the position of Fig. 5.

When the roll 6 is raised to the position of Fig. 6 the removal of the roll 6 from the roll 7 permits the springs 11 to rock the arms 9 clockwise until the sheet 58 is gripped between the rolls 59 and 60.

At the same time the movement of the handle 41 which raises the roll 6 to the highest position shown in Fig. 6 is utilized to connect the roll 59 to a source of power to rotate said roll in a direction to feed the double sheet 58 into printing position under the platen 740.

To this end the pulley 30 which is used to drive the roll 21 is provided with clutch dogs (not shown) on the side opposite from the clutch dogs 30a already described and the counterclockwise movement of the handle 41 shifts the pulley 30 to a position in which the dogs 30b engage with clutch dogs on a pulley 78 driven by the belt 57 already referred to.

When the handle 41 is moved counterclockwise the screw 53a, towards the end of the movement, engages the tail 52, rocking it counterclockwise, whereby the pulley 30 is shifted to cause its dogs to engage with the dogs on the pulley 78.

The belt 57 passes over a pulley 79 mounted on shaft 790 which is rotated by any suitable prime mover, and also over both pulleys 56 and 78 and over a tensioning pulley 80, the belt passing over the pulleys 56 and 78 in opposite direction, so that one pulley 56 is rotated in one direction and the other 78 in the opposite direction.

Thus the pulleys 56 and 78 constitute a reversing gear controlled by the handle 41.

When the pulley 30 is moved so that its dogs engage with the dogs on the pulley 78 as just described, it is rotated in a direction such that it turns the roll 59 in a clockwise direction to feed the double sheet 58 under the platen 740.

The double sheet is fed under the platen to an extent determined by a sensing pin which will be later described and the handle 41 is then returned to its middle position, whereby the roll 6 is brought down on to the sheets, there being four sheets between it and the roll 7, i. e. the journal sheet 1, the form sheet 2, and the two portions of the double sheet 58.

Printing on the sheets is now effected by actuation of the printing hammers. This operation forms no part of the present invention and will not be described here, save to state that the printing can be carried out by the mechanism described in British Patent specification No. 377,957.

After the printing operation has been completed the handle is moved clockwise whereby the feed roll 6 is raised to the intermediate position shown in Fig. 5 in which the arms 23 are pulled over by spring 50 until the auxiliary rolls 21 grip the form sheet 2 against the small rolls 17. Also the raising of the roll 6 permits the roll 60 to rise until the sheet 58 is gripped between this roll 60 and the roll 59.

Simultaneously the clockwise movement of the handle 41 causes engagement of the dogs on pulley 30 with the dogs on pulley 78, whereby the roll 59 is rotated to feed the double sheet 58 out in a direction opposite from that in which it was

fed in. Further, the auxiliary rolls 21, being in engagement with the form sheet 2, the latter is given a long feeding movement until arrested by the holes 31 registering with the small rolls 17 as already described.

Thus, movement of the handle 41 in a clockwise direction not only feeds the double sheet 58 out but also effects a long feeding movement of the form sheet 2.

In connection with the stopping of the sheet 58 when it reaches the printing position, it should be noted that the invention is mainly applicable to the case in which sheets already bearing a series of items are to be inserted in the machine for the purpose of having a further item or items printed below those already existing. In such a case the sheet must be fed in until it reaches a position in which the printing line is immediately below the last printed item on the sheet.

To this end a punching device is provided which, at the printing of each item, automatically punches a hole in the margin of the sheet in a predetermined position, and further a spring influenced sensing pin 81 is provided to sense the hole already punched at the last printing operation and on passing through the hole stops rotation of the feed roll 59, thereby arresting the sheet 58.

In the construction shown in the drawings the punching mechanism comprises a hollow punch 82 (Fig. 10) slidable in a vertical tubular guide 83 and carrying an upwardly directed lug 84. Within the hollow punch 82 slides the sensing pin 81, of which the operation will be described in detail later.

The lug 84 is provided with a slot with which engages a guide pin 85 and the lug is pivoted at its upper end to a lever 86 pivoted at one end to a bracket 87 (Figure 3) on the machine frame, and at the other end to a link 88 connecting it to one arm 89 of a bell crank pivoted on the shaft 878 of the machine described in British Patent specification No. 377,957. The other arm 90 of the bell crank co-operates with a cam 91 on the balance shaft 29 of the machine described in Patent Specification No. 377,957.

The punch is thus operated each time a balance is printed and a hole produced in the double sheet 58 in a particular position relative to each balance printed.

This hole is utilized in conjunction with the sensing pin 81 about to be described, to arrest the movement of the double sheet 58 when being fed into the platen.

The sensing pin 81 is mounted to slide within the hollow punch 82 and is pivoted to the end of an arm 92 secured to a shaft 93 carried in bearings 94 on the machine frame. Also secured to this shaft is a pawl 95 adapted to co-operate with a ratchet 96 on the shaft 24 of the roll 59. The pawl 95 has a tail 97 against which bears the end of a rod 98, of which the other end passes through a lug 99 on an arm 101 secured to the triangular plate 51 which is operated by the control handle 41.

Secured to the rod 98 adjacent the lug 99 is a collar 102, so that when the handle 41 is turned in the counter-clockwise direction to raise the roll 6 to the highest position shown in Figure 6, and also to feed the sheet 58 into the platen, the arm 101 is turned and its lug 99 acts on the collar 102 on rod 98 to pull rod 98 to the right in Figure 2. By this means the end of rod 98 is removed from contact with the tail 97 of pawl 95, whereupon a spring 103 attached to the tail 75

97 of pawl 95 and to a collar 104 on the rod 98, rocks the shaft 93 until the sensing pin 81 engages with the sheet 58. Engagement of the pin 81 with the sheet thus maintains the pawl 95 out 5 of engagement with the ratchet 96 during the operation of feeding the sheet 58 into the platen.

As soon as the sheet has been fed until the hole which was last punched therein registers with the sensing pin 81, the pin 81 passes through the 10 hole under the action of the spring 103 which rocks the pawl 95 and shaft 93 until pawl 95 engages with the ratchet 96 and arrests the rotation of the shaft 24 and feed roll 59 and consequently also arrests the feed of the sheet 58.

15 When the handle 41 is returned to its normal position the rod 98 is also returned by a spring 105.

In order to ensure withdrawal of the punch 82 a pin 106 is secured to the lever 901 which, as 20 described in British Patent specification No. 377,-957 effects the line spacing operation. Pivoted on this pin by means of a slot 107 is a lever 108 pivoted to a lever 109 which is pivoted between its ends to a bracket 110 on the arm 903 described 25 in British Patent specification No. 377,957. The other end 111 of lever 109 rests behind the friction roll on the end of the bell crank arm 90. When, therefore, the arm 901 is returned after a line spacing operation the lever 109 is rocked 30 and its end 111 positively rocks the bell crank arm 90 to withdraw the punch if this has not already been effected by the spring 112.

While there are above described but a limited 35 number of embodiments of the invention, it is possible to produce still other embodiments without departure from the inventive concept above disclosed, and it is, therefore, desired that only such limitations shall be imposed on the appended 40 claims as are stated therein, or required by the prior art.

I claim:—

1. A paper feeding device comprising in combination, means for feeding a duplex sheet of record paper into a printing mechanism in a direction opposite to that of normal feeding, means for separating said duplex sheet to receive a duplicating medium, said means comprising a dividing element positioned adjacent an ink ribbon to cause the upper and longer fold of said duplex sheet to pass above said dividing element, and above said ink ribbon while the lower and shorter fold passes below, and means for feeding said sheet into printing position in one direction and out of printing position in the opposite direction.

2. A paper feeding device comprising the combination of means for guiding a plurality of continuous paper webs between a plurality of ink ribbons, means for feeding one of said paper webs alternately either line by line or continuously over the space of a plurality of lines, means for feeding a duplex sheet of record paper into a printing mechanism in a direction opposite to that of normal feeding, means for separating

said duplex sheet to receive a duplicating medium, said means comprising a dividing element positioned adjacent an ink ribbon to cause the upper and longer fold of said duplex sheet to pass above said dividing element, and above said ink ribbon while the lower and shorter fold passes below, means for feeding said sheet into printing position in one direction and out of printing position in the opposite direction, and a single manipulative means for controlling the functioning of the above named means. 5

3. A paper feeding device comprising in combination, clutch controlled power driven means for feeding a duplex sheet of record paper into a printing mechanism in a direction opposite to that of normal feeding and out of printing position in the opposite direction, means for separating said duplex sheet to receive a duplicating medium, said means comprising a dividing element positioned adjacent an ink ribbon to cause the upper and longer fold of said duplex sheet to pass above said dividing element and above said ink ribbon while the lower and shorter fold passes below, and manipulative means for controlling the functions of the above named means. 10

4. A paper feeding device comprising in combination, feed rolls adapted to feed a continuous record sheet line by line, feed rolls adapted to feed a bill form line by line during item entry and continuously over a plurality of lines when the entries on a bill are complete, feed rolls adapted to feed a duplex record form into printing position in a direction opposite to normal feeding and out of printing position in the normal feeding direction, clutch controlled power driven means for effecting the continuous feed of said bill form over a plurality of lines and the feeding of said duplex form in both directions and a single manipulative means for effecting control of said clutch and to position said feed rolls appropriately to permit the above named feeding operations. 20

5. A paper feeding device comprising in combination, a plurality of pairs of feed rolls; mechanism adapted to effect step-by-step actuation of one of said pairs of rolls; means for effecting the actuation of the other of said pairs of feed rolls; a prime mover; a clutch device for connecting said prime mover and said means for actuating said feed rolls; and means settable in three positions, in the first of which said first mechanism only is rendered effective, in the second of which said means renders said first mechanism ineffective and causes one of the other of said pairs of feed rolls to be clutched to said prime mover 30 and to be operated in a direction opposite to the normal feeding direction, and in the third of which said means renders said first mechanism ineffective, causes the reversal of operation of said clutch to drive the second said pair of feed rolls in normal feeding direction and concomitantly causes the actuation of another of said pairs of feed rolls. 40

FRANCISCO CAMPOS.
